ADJUSTABLE LEVERAGE CLAW HAMMER

Ray W. Johnson, San Jose, Calif., assignor to
Le Tourneau, Inc., Longview, Tex.

Application August 24, 1951, Serial No. 243,560

6 Claims. (Cl. 254—26)

1

This invention relates to a claw hammer with adjustable leverage. This application is a combination in part of application Serial No. 161,629, filed May 12, 1950, for Claw Hammer with Adjustable Leverage Fulcrum.

The primary object of the invention is to provide a hammer which has on it an adjustable fulcrum member adapted to be held rigidly in its adjusted position, and which is adjustable to permit of its being projected beyond the top of the hammer so as to produce selected varying increased leverage power for removing nails, whereby nails of varying length may be drawn without danger of breaking the hammer claws or bending the nails; said fulcrum member having such connection with the head of the hammer that in its retracted position it does not form an obstruction in the ordinary use of the hammer.

Another object of the invention is to provide a fulcrum attachment on the head of a claw hammer for adjusting the leverage of the hammer with respect to the claws in accordance with the length of the nails to be pulled, and to support said fulcrum member so that it straddles the head of the hammer and is positively held in adjusted position, but is easily released for varying the adjustment.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawings.

With the foregoing and other objects in view, which will be made manifest in the following detailed description, reference is had to the accompanying drawings for the illustrative embodiment of the invention, wherein:

Fig. 1 is a side view of the head of the hammer showing the fulcrum member in extended operative position.

Fig. 2 is a plan view partly in section of the head of the hammer with said fulcrum member attachment thereon.

Fig. 3 is a sectional view through the hammer section being taken generally through the lines 3—3 of Fig. 1.

Fig. 4 is a side view of the head of the hammer

2

showing the fulcrum member in collapsed position and showing a modified holding pivot for said attachment.

In the illustrative embodiment of my invention the head 1 of a hammer is provided with the usual handle 2. The head 1 has the usual heel portion 3 and claw portion 4. The top edge of the hammer is recessed to form a socket 6 to accommodate a fulcrum member 7 on the middle portion of the head 1.

The fulcrum member 7 is of generally U-shaped cross-section so that it straddles the middle portion of the head of the hammer. The sides or wings 8 extend from the opposite sides of a bearing surface or top 9. This top 9 is suitably curved to conform to the general shape of the top of the hammer head 1. An arm 11 extends from each wing 8 immediately adjacent to the top 9 toward the heel 3. A pivot pin 12 extends through the ends of the arms 11 and also through a slot or hole 13 adjacent the heel 3 of the hammer head 1, which slot 13 is elongated generally from the heel 3 toward the middle of the head 1. Thus the fulcrum member 7 is pivoted on a pivot 12 which can be shifted in the elongated slot 13 longitudinally with respect to the hammer head 1.

In each wing 8 of the fulcrum member 7 is a generally arcuate slot 14. The edge of each arcuate slot 14 nearer to the free edge 16 of the wing 8 is scalloped. The scalloped edge is formed by a series of spaced keeper notches 17. A locking pin 18 is fixed in the hammer head and extends beyond the opposite sides of the hammer and into the respective slots 14 of the attachment wing 8. The holding pin 18 is in substantial axial alignment with the center of the pivot slot 13 so that as the attachment fulcrum member 7 is pulled toward the claws 4 its pivot 12 slides in the elongated pivot slot 13 and thus the respective notch 17 can be disengaged from the holding pin 18 allowing the swinging of the fulcrum member around until an adjusted selected position is reached and another keeper notch 17 is brought opposite the holding pin 18. Thereupon the wing 8 is shifted so that the pivot 12 returns to the initial position shown in Fig. 1 and the selective notch 17 is thus pulled into engagement with the holding pin 18 to hold the fulcrum member 7 in the selected adjusted position.

In the form shown in Fig. 1 means are provided to prevent the accidental releasing of the fulcrum member 7 in the form of an abutment pin 19 adjacent the outer edge 16 of one of the wings 8. This abutment pin 19 is slidable in a socket 21 in the side of the hammer adjacent said

wing 8. The outer end of the pin 19 is reduced in diameter so as to form a shoulder 22. A coil spring 23 inside of the socket 21 normally urges the pin 19 outwardly of said socket or hole 21. The socket or hole 21 and the pin 19 are so spaced from the outer end of the pivot slot 13 that the distance is shorter than the distance between the fulcrum pin 12 and the outer edge 16 of the attachment wing 8. Thus the attachment wing 8 projects over the shoulder 22 of the abutment pin 19 and prevents the accidental removal of said abutment pin 19. At the same time the reduced projecting end of the abutment pin 19 prevents the shifting of the fulcrum member 7 relatively to the elongated fulcrum slot 13.

In order to adjust the fulcrum member 7 as heretofore described it is necessary in this form to depress the abutment pin 19 against the action of the coil spring 23 until the reduced projecting end of the pin 19 is concealed within the socket 21 leaving the fulcrum member 7 free for shifting longitudinally relatively to the notch 13 and out of engagements with the holding pin 18. After the fulcrum member 7 is adjusted to a new position, the abutment pin 19 is released and its shoulder abuts against the underside of the adjacent wing 8. The reduced end or projecting portion of the pin 19 engages the outer edge 16 of said wing 8 and thus holds the fulcrum member 7 against shifting on the hammer head 1.

The modified form of the invention shown in Fig. 4 includes the fulcrum member 7, the holding pin 18, the pivot pin 12 and the elongated pivot slot 13 but it eliminates the abutment pin 19. A coil spring 26 in the elongated pivot slots 13 bears against an end of said slot 13 and against the pivot pin 12 so as to normally urge the pivot pin 12 outwardly toward the heel 3 of the hammer head 1 and thus to normally urge the aligned keeper notch 17 into engagement with the holding pin 18. In this form the fulcrum member 7 can be pulled against the action of the coil spring 13 so that the fulcrum 12 thereof is shifted toward the claws of the hammer head 1 until the keeper notch 17 is disengaged from the holding pin 18 and then the fulcrum member 7 is adjusted to the desired angle and another selected notch 17 is allowed to snap over the holding pin 18 under the action of the coil spring 26 in the elongated slot 13.

I claim:

1. In combination a claw hammer, a heel at one end thereof, claws at the other end thereof, said claw hammer having a hole therethrough, adjacent said heel extending from one face to the other face of said hammer head, said hole being elongated from said heel toward the middle of said hammer head, a fulcrum member, a pivot of said fulcrum member being slidable in said elongated hole, said fulcrum member including a bearing top generally conforming to the contour of the hammer head, a pair of spaced wings extended from said top over the opposite sides of the hammer head, each of said wings having an arcuate slot the arc of which is generally centered about the fulcrum of said fulcrum member, a plurality of keeper notches on the edge of said slot farthest from said fulcrum; an engagement pin extended through said hammer head and projecting beyond the opposite sides thereof and being generally longitudinally aligned with the fulcrum hole, and being adapted to be engaged by a selected keeper notch in said arcuate slot to prevent the pivoting of said ful-

crum member; and resiliently yieldable means to hold said fulcrum member in engagement with said engagement pin.

2. In combination a claw hammer, a heel at one end thereof, claws at the other end thereof, said claw hammer having a hole therethrough adjacent said heel extending from one face to the other face of said hammer head, said hole being elongated from said heel toward the middle of said hammer head, a fulcrum member, a pivot of said fulcrum member being slidable in said elongated hole, said fulcrum member including a bearing top generally conforming to the contour of the hammer head, a pair of spaced wings extended from said top over the opposite sides of the hammer head, each of said wings having an arcuate slot the arc of which is generally centered about the fulcrum of said fulcrum member, a plurality of keeper notches on the edge of said slot farthest from said fulcrum; an engagement pin extended through said hammer head and projecting beyond the opposite sides thereof and being generally longitudinally aligned with the fulcrum hole, and being adapted to be engaged by a selected keeper notch in said arcuate slot to prevent the pivoting of said fulcrum member; and resiliently yieldable means to hold said fulcrum member in engagement with said engagement pin, said resiliently yieldable means including a socket in a side of the hammer head adjacent the outer edge of one of said wings, an abutment element slidable in said socket, a spring within the socket normally urging said abutment element outwardly toward the adjacent wing, a shoulder on said abutment element extended under the adjacent wing to limit its outward movement, and an extension at said shoulder engaged by the outer edge of said wing to prevent shifting of the fulcrum member with respect to said pivot hole.

3. In combination a claw hammer, a heel at one end thereof, claws at the other end thereof, said claw hammer having a hole therethrough adjacent said heel extending from one face to the other face of said hammer head, said hole being elongated from said heel toward the middle of said hammer head, a fulcrum member, a pivot of said fulcrum member being slidable in said elongated hole, said fulcrum member including a bearing top generally conforming to the contour of the hammer head, a pair of spaced wings extended from said top over the opposite sides of the hammer head, each of said wings having an arcuate slot the arc of which is generally centered about the fulcrum of said fulcrum member, a plurality of keeper notches on the edge of said slot farthest from said fulcrum; an engagement pin extended through said hammer head and projecting beyond the opposite sides thereof and being generally longitudinally aligned with the fulcrum hole, and being adapted to be engaged by a selected keeper notch in said arcuate slot to prevent the pivoting of said fulcrum member; and resiliently yieldable means to hold said fulcrum member in engagement with said engagement pin, said resiliently yieldable means including a coil spring in said elongated pivot hole for resiliently pressing said fulcrum pivot against the end of said hole adjacent the heel of the hammer head.

4. A fulcrum attachment device for the head of a claw hammer having a heel at one end and claws at the other end thereof, comprising a fulcrum member having a curved bearing base generally fitting over the top of the hammer

head, a pair of wings extended from said base for straddling the hammer head between said heel and said claws, a pair of arms extended from said wings, said hammer head having a hole adjacent the heel thereof extending transversely through the opposite faces of the hammer head and being elongated toward the middle of the hammer head, a pivot element extended through said arms and through said hole to pivot said fulcrum member, each wing having an arcuate slot therethrough the arc of which is generally centered about said pivot element, a plurality of keeper notches spaced on the edge of the slot farthest from said pivot element, a holding pin extended through said hammer head between the center of said hammer head and the claws and being generally aligned with said elongated hole and fitting into the respective keeper notches, and resiliently yieldable means to hold a selective keeper notch in engagement with said holding pin.

5. A fulcrum attachment device for the head of a claw hammer having a heel at one end and claws at the other end thereof, comprising a fulcrum member having a curved bearing base generally fitting over the top of the hammer head, a pair of wings extended from said base for straddling the hammer head between said heel and said claws, a pair of arms extended from said wings, said hammer head having a hole adjacent the heel thereof extending transversely through the opposite faces of the hammer head and being elongated toward the middle of the hammer head, a pivot element extended through said arms and through said hole to pivot said fulcrum member, each wing having an arcuate slot therethrough the arc of which is generally centered about said pivot element, a plurality of keeper notches spaced on the edge of the slot farthest from said pivot element, a holding pin extended through said hammer head between the center of said hammer head and the claws and being generally aligned with said elongated hole and fitting into the respective keeper notches, and resiliently yieldable means to hold a selective keeper notch in engagement with said holding pin, said last means including a socket in one side of the hammer head adjacent the claws, an abutment pin slidable in the socket, a spring to normally urge

the abutment pin outwardly toward the adjacent wing of the fulcrum member, a reduced projecting end on said abutment pin extending against the outer edge of the adjacent wing to prevent its movement with respect to said elongated hole, the said abutment pin being adapted to be concealed when pressed into said socket to allow the shifting of the fulcrum member with respect to said elongated hole for disengaging the keeper notch from the holding pin and adjusting the angle of said fulcrum member.

6. A fulcrum attachment device for the head of a claw hammer having a heel at one end and claws at the other end thereof, comprising a fulcrum member having a curved bearing base generally fitting over the top of the hammer head, a pair of wings extended from said base for straddling the hammer head between said heel and said claws, a pair of arms extended from said wings, said hammer head having a hole adjacent the heel thereof extending transversely through the opposite faces of the hammer head and being elongated toward the middle of the hammer head, a pivot element extended through said arms and through said hole to pivot said fulcrum member, each wing having an arcuate slot therethrough the arc of which is generally centered about said pivot element, a plurality of keeper notches spaced on the edge of the slot farthest from said pivot element, a holding pin extended through said hammer head between the center of said hammer head and the claws and being generally aligned with said elongated hole and fitting into the respective keeper notches, and resiliently yieldable means to hold a selective keeper notch in engagement with said holding pin, said resilient means comprising a spring between said pivot element and the end of the hole nearer the middle of the hammer head for resiliently urging the pivot element and the fulcrum member toward the heel of the hammer head.
